FUEL PUMP

Harry J. Welch, Walled Lake, Mich., assignor to
 Novi Equipment Company, Novi, Mich., a corporation of Michigan

Application March 31, 1947, Serial No. 738,417

10 Claims. (Cl. 103—154)

1

This invention relates generally to pumps and refers more particularly to improvements in fuel pumps for use in connection with the induction system of internal combustion engines.

In many types of internal combustion engines, it is the practice to draw fuel from a suitable source of supply and to force it into the float chamber of the carburetor by a pump. Pumps employed in the past for the above purpose are usually of the diaphragm type and are operated from the cam shaft of the engine. Although such pumps are used extensively to transfer fuel from the source to the induction system of an internal combustion engine, they nevertheless, possess numerous shortcomings. In the first place the pump diaphragms are inherently not very durable and failure of the pump may be frequently traced to defective diaphragm performance. In the second place, diaphragm pumps are usually of fixed capacity and must be replaced by larger or smaller pumps to suit different pressure requirements. Thus in instances where engines having different fuel pump pressure requirements are manufactured or serviced, it is necessary to provide a large inventory of fuel pumps.

One of the objects of this invention is to overcome the above objections by providing a piston type fuel pump wherein the piston is moved on its suction stroke by power means such for example as the cam shaft of an internal combustion engine and wherein a spring is provided for moving the piston on its pressure stroke. The spring is calibrated in accordance with the pressure requirements at the delivery side of the pump and is readily interchangeable with springs having different strength characteristics. Thus one pump model may be employed to produce different delivery pressures by merely interchanging the springs. Moreover, piston type pumps are inherently more durable than diaphragm operated pumps and, as a result, assure continued service over long periods without attention.

Another feature of this invention is to provide a pump assembly wherein the spring for moving the piston on its pressure stroke is interposed between the piston and a cap readily removably clamped to one end of the pump cylinder for closing the latter end. Thus the spring may be quickly removed and exchanged for another spring by merely detaching the cap from the cylinder.

A further feature of the present invention is to provide a pump assembly having inlet and outlet passages communicating with the cylinder at one end of the piston and respectively controlled by

2

check valves alternatively movable to their open positions upon movement of the piston in opposite directions in the cylinder.

Still another feature of this invention is to provide a pump assembly having a cup-shaped piston and having a valve carrying body forming with the inner wall of the cylinder an annular space for slidably receiving the skirt portion of the piston. Actually the opposite sides of the piston skirt respectively slidably engage the inner wall of the cylinder and the outer wall of the valve carrying body with the result that the piston is effectively supported during operation thereof.

A still further object of this invention is to provide a pump assembly of the type previously set forth composed of a relatively few simple parts capable of being inexpensively manufactured and assembled to form a compact structure.

The foregoing as well as other objects will be made more apparent as this description proceeds, especially when considered in connection with the accompanying drawings, wherein:

25 Figure 1 is an elevational view of a pump assembly embodying the features of this invention;

Figure 2 is a top plan view of the pump assembly shown in Figure 1;

Figure 3 is a sectional view taken substantially on the line 3—3 of Figure 2;

Figure 4 is a sectional view taken on the line 4—4 of Figure 2;

Figure 5 is a sectional view taken on the line 5—5 of Figure 2;

Figure 6 is a sectional view taken on the line 6—6 of Figure 2;

Figure 7 is a cross sectional view taken on the line 7—7 of Figure 3; and

Figure 8 is a sectional view taken on the line 8—8 of Figure 5.

The pump assembly shown in the drawings for the purpose of illustrating this invention comprises a casing 10, a body member 11 and a piston 12. In the interests of manufacture on a production basis, both the casing and body member may be die cast, although any other suitable method of manufacture may be resorted to without departing from the spirit and scope of this invention.

50 The casing 10 is formed with a cylinder 13 at the upper end and is provided with a reduced attaching portion 14 at the lower end. The upper end of the cylinder 13 is open and the lower end is closed by a wall 15 of the reduced portion. The reduced portion 14 is formed with circum-

dentially spaced bosses 16 and 17, respectively, having inlet and outlet ports 18 and 19 therein. The ports respectively communicate with vertical passages 20 and 21 extending upwardly through the wall 15. The wall 15 is cored out between the passages in the manner indicated by the reference character 22 in Figures 3 and 4 of the drawings to reduce the weight of the part to a minimum. It will also be noted from the above figures of the drawings that the portion 14 is provided with diametrically opposed attaching flanges 23 and is centrally bored to enable extending a piston operating rod 24 therethrough. Actually the bore is enlarged in diameter for a substantial distance from the upper end to accommodate a sleeve 25 of wear resisting material and the rod 24 is slidably supported in the sleeve.

The casing 10 is formed with a radially outwardly extending annular flange 26 at the top of the cylinder 13 and a cap 27 is clamped to the flange 26 to close the open end of the cylinder. As shown in Figure 4 of the drawings, the cap 27 is frustro-conical in shape having a radially outwardly extending annular flange 28 at the lower end adapted to seat on the flange 26 and having a flat top wall 29. The cap 27 is removably clamped in place on the cylinder 13 by a bracket comprising a strap 30 extending over the cap 27 and having lugs 31 at the outer ends adapted to engage the underside of the flange 28 at diametrically opposite points. The central portion of the strap is located directly above the flat wall 29 of the cap 27 and a nut 32 is secured thereto for threadably receiving a thumb screw 33. The lower end of the screw 33 abuts the wall 29 at the center thereof and serves to clamp the flange 28 on the cap against the flange 26. In practice an annular sealing gasket is positioned between the flange 26 on the casing and the flange 28 on the cap to prevent the escape of fluid out of the top of the cylinder.

The body member 11 is cylindrical and is seated on the wall 15 of the casing in concentric relation to the cylinder 13. The diameter of the body 11 is somewhat less than the internal diameter of the cylinder and cooperates with the latter to provide an annular space 34. The central portion of the body is bored in axial alignment with the bore in the casing to permit extending the rod 24 therethrough into the cylinder 13. The diameter of the bore through the body 11 is greater than the diameter of the bore through the casing to receive a sleeve 35 of wear resisting material and the inside diameter of the sleeve is such as to telescopically engage the upper end of the sleeve 25. The sleeve 35 extends upwardly beyond the corresponding end of the sleeve 25, and a fitting 36 is brazed or otherwise secured to the upper end of the sleeve 35. The fitting 36 is secured to the piston 12, so that the latter, fitting 36 and sleeve 35 form an assembly. The top of the sleeve 25 forms a seat for engagement with a head 37 at the top of the piston rod 24 to locate the piston 12 in its lowermost position in the cylinder 13 and the fitting 36 acts as an abutment for engagement with the head 37 to move the piston assembly upwardly in the cylinder.

Referring again to Figure 4 of the drawings, the body member 11 is detachably secured to the wall 15 of the casing by studs 38 having the head portions accessible through the cored out openings 22 in the portion 14 of the casing. In this connection it will be noted from both Figures 3 and 4 of the drawings that the body member 11

is also cored out wherever it is possible, to reduce the weight of the assembly to a minimum. The body is also formed with a pair of vertically extending passages 39 and 40 respectively forming continuations of the passages 20 and 21. The upper end of the passage 39 is counterbored to receive a check valve assembly 41 movable to its open position in response to movement of the piston 12 on its suction stroke in an upward direction in the cylinder 13 and movable to its closed position upon movement of the piston on its pressure stroke in a downward direction in the cylinder.

The valve assembly 41 comprises an inverted cup-shaped casing 42 threadably engaging internal threads on the inner wall of the counterbore at the upper end of the passage 39 and having laterally spaced openings 43 in the base portion. The lower or open end of the casing 42 is closed by a plate 44 suitably secured in the open end of the casing and having a central opening 45 therethrough registering with the upper end of the passage 39. A flat polygonally shaped disc type valve member 46 is positioned within the casing 42 for vertical movement between the plate 44 and the base of the casing.

When the piston 12 is on its pressure stroke, the valve member 46 seats on the plate 44 and closes the opening 45 or passage 39. On the other hand, when the piston 12 is on its suction stroke, the valve member 46 is moved upwardly against the base of the casing 42. Due to the flats on the valve member 46 and due to the size of the openings 43, clearance is provided to enable fluid to flow from the upper end of the passage 39 past the valve assembly 41 and into the space below the piston head.

A similar check valve assembly 48 is provided at the top of the outlet passage 40 and corresponding parts of the assembly 48 are indicated by the same reference numerals. It will be noted from Figure 6, however, that the check valve assembly 48 is inverted with respect to the check valve assembly 41, so that the disc valve in the check valve assembly 48 opens in response to movement of the piston 12 on its pressure stroke.

The piston 12 is of inverted cup-shaped configuration having a head 53 and a skirt 54. The skirt 54 projects into the annular space 34 with the inner and outer surfaces respectively slidably engaging the body 11 and adjacent wall of the cylinder 13. Thus the piston is effectively guided throughout its travel in the cylinder and leakage of fluid past the piston is minimized. In this connection it will be noted that any fluid leaking past the piston escapes into the inlet passage 18 through passages 18' formed in the reduced portion 14 of the casing. These passages also serve as bleed openings to prevent trapping air into the space 34 below the piston skirt 54.

The head 53 of the piston is formed with an annular groove 55 forming a seat for the lower end of a coil spring 56 having the upper end abutting the top wall 29 of the cap 27. The spring 56 is the power means for moving the piston 56 downwardly on its pressure stroke, and is calibrated to suit the pressure required at the delivery side of the pump. This spring is positioned to be readily accessible upon removing the cap 27 and may be quickly replaced by a spring having different strength characteristics by merely removing the cap 27.

It has previously been stated that the piston 12 is moved upwardly in the cylinder 13 on its suction stroke by the push rod 24. Any suitable

means may be provided for operating the rod 24, and accordingly, this disclosure is not complicated by a detailed illustration of such means. It will suffice to point out that the rod 24 is moved upwardly by a push rod 57 having the upper end engaging the lower end of the rod 24 and having the lower end engaging a cam (not shown) operated by the internal combustion engine in accordance with conventional practice. Actually the upper end of the push rod 57 slidably engages within a fitting 58 suitably secured to the lower end of the piston rod 24 and having a portion forming a shoulder 59 for the lower end of a coil spring 60. The upper end of the coil spring 60 abuts a washer 61 engaged with the bottom of the casing 16 with the result that the spring 60 tends to hold the head 31 on the piston rod in engagement with the seat provided at the top of the sleeve 25. Thus the spring 60 acts as a return spring for the piston rod 24 and maintains the lower end of the latter in operative relationship to the push rod 57.

Operation

In the event the pump is employed for the purpose of supplying fuel to the carburetor of an internal combustion engine, the inlet port 18 is connected to a source of fuel supply and the outlet port 19 is connected to the carburetor. With this in view, it will be noted that each time the rod 24 is moved upwardly from the position shown in Figure 3 of the drawings, the piston 12 is also moved upwardly in the cylinder 13. Upward movement of the piston in the cylinder effects a reduction in pressure in the cylinder below the head 53 of the piston 12, and the resulting suction not only opens the check valve 41, but also draws fuel into the cylinder below the piston head through the inlet passage 20, 39.

When the piston 12 reaches the end of its suction stroke, the rod 24 is moved downwardly by the coil spring 60, and the piston is moved on its pressure stroke by the coil spring 56. As a result a pressure is created in the cylinder 13 below the piston head 53 proportionate to the strength of the coil spring 56, and the check valve 48 is opened. During this cycle of operation the check valve 41 is, of course, closed, and fuel previously admitted by the check valve 41 is forced out of the outlet port 19 through the outlet passages 40, 21.

What I claim as my invention is:

1. A pump comprising a casing having a cylinder, a body member supported within the cylinder in concentric relation to the inner wall of the cylinder and cooperating with said inner cylinder wall to form an annular space, inlet and outlet passages formed in the body and communicating with the interior of the cylinder, a piston having a cylindrical skirt slidably supported in the annular space aforesaid and in slidable engagement with both the inner and outer walls of said space, said piston having a head portion located between said body and one end of the cylinder, means for reciprocating said piston, and check valves supported by the body member in positions to alternatively open and close the passages upon movement of the piston in opposite directions in the cylinder.

2. A pump comprising a casing having a cylinder open at one end, a body member supported within the cylinder in concentric relation to the inner wall of the cylinder and cooperating with said inner cylinder wall to form an annular space, inlet and outlet passages formed in said

body member and communicating with the interior of the cylinder, a piston having a cylindrical skirt in slidable engagement with both the inner and outer walls of said annular space and having a head portion positioned between the body member and open end of the cylinder, check valves supported by the body member in positions to alternatively open and close the passages upon movement of the piston in opposite directions in the cylinder, positive acting means for moving said piston on its suction stroke, a cap readily removably secured to the open end of the cylinder, and a spring calibrated in accordance with the pressure requirements at the delivery side of the outlet passage and located between the cap and piston for moving the latter on its pressure stroke in a direction toward the body member.

3. A pump comprising a casing having a cylinder, a body member supported within the cylinder in concentric relation to the inner wall of the cylinder and cooperating with said inner cylinder wall to form an annular space, inlet and outlet passages formed in the body and communicating with the interior of the cylinder, a piston having a cylindrical skirt slidably engaging both the inner and outer walls of the annular space aforesaid and having a head portion located between said body and one end of the cylinder, means for reciprocating said piston, check valves supported by the body member in positions to alternatively open and close the passages upon movement of the piston in opposite directions in the cylinder, the engagement between said skirt and said walls constituting a seal which permits some leakage, and a bleed passage connecting said annular space below the piston skirt to the inlet passage.

4. A pump comprising a cylinder having a closed end, a cylindrical body in said cylinder defining an annular space therewith and having an end wall spaced from the closed end of said cylinder, a piston reciprocable in said cylinder between said body and the closed end of said cylinder and having a skirt slidably engaging both the inner and outer walls of the annular space, inlet and outlet check valves controlling fluid flow into the space between the end wall of said body and said skirted piston, said body having an axially extending opening therethrough, and a piston rod acting against the inside of said skirted piston reciprocable therein.

5. A pump comprising a cylinder having a closed end, a cylindrical body in said cylinder defining an annular space therewith and having an end wall spaced from the closed end of said cylinder, a piston reciprocable in said cylinder between said body and the closed end of said cylinder and having a skirt slidably engaging both the inner and outer walls of the annular space, inlet and outlet check valves controlling fluid flow into the space between the end wall of said body and said skirted piston, said body having an axially extending opening therethrough, and a piston rod acting against the inside of said skirted piston reciprocable therein, said piston rod having one way engagement with said piston to move said piston away from said body, and spring means between the closed end of said cylinder and said piston for returning said piston toward said body.

6. A pump comprising a cylinder having a closed end, a cylindrical body in said cylinder defining an annular space therewith and having an end wall spaced from the closed end of said cylinder, a piston reciprocable in said cylinder be-

tween said body and the closed end of said cylinder and having a skirt slidably engaging both the inner and outer walls of the annular space, inlet and outlet check valves controlling fluid flow into the space between the end wall of said body and said skirted piston, said body having an axially extending opening therethrough, and a piston rod acting against the inside of said skirted piston reciprocable therein, said piston rod having one way engagement with said piston to move said piston away from said body, and spring means between the closed end of said cylinder and said piston for returning said piston toward said body, said body having an annular sleeve extending in the opening in said body toward said piston and slidably engaged by said piston rod, and an annular sleeve extending outwardly from the inside of said piston and slidably engaging the outer surface of said first sleeve and the inner surface of said opening.

7. A pump comprising a cylinder having a closed end, a cylindrical body in said cylinder defining an annular space therewith and having an end wall spaced from the closed end of said cylinder, a piston reciprocable in said cylinder between said body and the closed end of said cylinder and having a skirt slidably engaging both the inner and outer walls of the annular space, inlet and outlet check valves controlling fluid flow into the space between the end wall of said body and said skirted piston, and means for reciprocating said piston, the closed end of said cylinder being constituted by a removable cap, a strap having its ends shaped to engage with the outer surface of said cylinder, and a single clamping screw carried by said strap and engageable with said cap to press said cap on said cylinder in closing relation to an end thereof.

8. A pump comprising a cylinder having a closed end, a cylindrical body in said cylinder defining an annular space therewith and having an end wall spaced from the closed end of said cylinder, a piston reciprocable in said cylinder between said body and the closed end of said cylinder and having a skirt slidably engaging both the inner and outer walls of the annular space, inlet and outlet check valves controlling fluid flow into the space between the end wall of said body and said skirted piston, and means for reciprocating said piston, said valves being located in the end wall of said body.

9. A pump comprising a skirted piston having an annular skirt and an annular sleeve concentric with said skirt, a piston rod for reciprocating said piston concentric with and spaced inwardly

5 from said sleeve, a cylinder within which said piston is reciprocable, a cylindrical body fixed within said cylinder and having its outer wall in sliding contact with the inner wall of said skirt, said body having a cylindrical opening therein, the wall of which is in sliding contact with the outer surface of said sleeve, a tubular guide fixed in said opening and having its outer surface in sliding contact with the inner surface of said sleeve, said piston rod being reciprocable within said guide sleeve, check valve controlled inlet and outlet passages for the flow of fluid through the space defined between said body and said piston, and means for reciprocating said piston.

10. A pump comprising a skirted piston having an annular skirt and an annular sleeve concentric with said skirt, a piston rod for reciprocating said piston concentric with and spaced inwardly from said sleeve, a cylinder within which said piston is reciprocable, a cylindrical body fixed within said cylinder and having its outer wall in sliding contact with the inner wall of said skirt, said body having a cylindrical opening therein, the wall of which is in sliding contact with the outer surface of said sleeve, a tubular guide fixed in said opening and having its outer surface in sliding contact with the inner surface of said sleeve, said piston rod being reciprocable within said guide sleeve, check valve controlled inlet and outlet passages for the flow of fluid through the space defined between said body and said piston, bleed passages connecting the annular spaces within which said skirt and sleeve are slidably to the inlet passage, and means for reciprocating said piston.
